W. M. Wilson

UNITED STATES PATENT OFFICE

WILLIAM GUMPRICH, OF BROOKLYN, NEW YORK, ASSIGNOR TO DAYTON SCALE COMPANY, OF DAYTON, OHIO, A CORPORATION OF NEW JERSEY

SHOCK ABSORBER FOR SCALES

Application filed March 23, 1929. Serial No. 349,393.

This case relates to weighing scales of the computing drum type in which an equalizer bar is provided to actuate the drum and a load-actuated draft member connected to the counterbalances is provided to actuate the equalizer bar.

In scales of this kind as at present constructed, the equalizer bar is seated between upper and lower knife edges of an adjustable hook movable as a unit with the draft member. It has been found that when a heavy load is suddenly dropped on the platform or suddenly taken off, the shock imposed on the equalizer bar through the knife edges may cause it to take a permanent set. As a result, the tendency for the bar to yield slightly under stress of a sudden change in load will be lost and repeated shocks will bend the bar throwing the scale off balance and making it difficult to readjust. Further, the failure of the bar to yield under a sudden load causes it to rotate the drum violently and abruptly thereby injuring the drum bearings. Again, the reaction of the nonyieldable bar when acted on by a sudden load upon the knife or pin bearing connection between the lever and the draft member will tend to injure said connection. Furthermore, when a sudden shock is imposed on the equalizer bar in known scales, the ends of the bars will whip downwardly or upwardly with the support of the center of the bar as a fulcrum. The bar will thus momentarily take the shape of a pair of oppositely inclined lines intersecting at the center of the bar. The ends of the bars have racks rigidly supported thereto at right angles thereto so that when the bar takes its inclined shape, the bars will also be moved to a position inclined to their normal vertical position.

The racks mesh with pinions on the drum chart shaft and when the racks move angularly, their teeth move angularly relatively to the pinion teeth and in some cases leave the pinion teeth altogether. Thus if a load is suddenly applied to the scale, the center of the equalizer bar will stop before the ends of the bar which will move downwardly inclining the bar and moving the racks downwardly and angularly outwardly. In so doing,

the rack teeth and the pinion teeth meshed therewith are liable to injury especially if the racks leave the pinions altogether whereupon they clash with the pinions on returning to meshing engagement. The same action, as above described, but in the reverse direction, occurs when a load is suddenly removed from the scale. It does not take many such sudden applications and removals of load to permanently injure the rack and pinion teeth on which the accuracy of the scale is primarily dependent.

The object of this invention is to provide a construction whereby the sudden application or removal of a heavy load will not tend to set or injure the equalizer bar and its associated elements.

Further, the object of the invention is to provide a yieldable, separate connection between the draft member and the equalizer rod of a drum scale.

Further and other objects and advantages will be hereinafter set forth in the accompanying specification and claims, and shown in the drawings, which by way of illustration show what is now considered to be the preferred embodiment of the invention.

Fig. 1 is a front elevation of the drum chart and the associated members;

Fig. 2 is a section on line 2—2 of Fig. 1;

Fig. 3 is a detail of the yieldable connection between the draft and equalizer rods.

Referring to the drawings in detail, the draft member 10 is connected to the base lever system (not shown) by a draft hook 11. Attached by screws 12 to the member 10 is the U-shaped draft bar 13 extending longitudinally of the drum and having connections 14 at each end to the counterbalancing springs 15. The member 10 has a round bore 16 in which is slidably adjustably mounted a spring depressed plunger 17. A screw 18 threaded in member 10 serves to adjust the plunger 17 to adjust the chart reading to zero. The upper end of the latter has pivotally pinned thereto a U-shaped member 19 extending parallel to and beneath member 13.

The top 20 of member 19 has at each end an opening 21, through which passes the shank of a member 23. On one side of the

opening and surrounding the shank of member 23 is a spring 22 and a similar spring 22' is on the other side of the opening also surrounding said shank. Member 23 has an annular portion 24 in which is seated the round equalizer bar 25. The springs 22 and 22' are disposed between and act at each end on plates 26 and 27 freely carried on the shank of members 23. A movement of member 19 will thus be communicated to member 23 through the springs 22 and 22' connecting the members 19 and 23. A sudden, violent, movement of member 19 will be absorbed by said springs which acts as shock absorbers.

15 The operation of the above mechanism is as follows:

When a load is placed on the platform, the draft rod 11 pulls member 10 downwardly against the resistance of counterbalancing 20 springs 15 connected to member 13 rigid with 10. Member 19 moves with member 10 and through springs 22 and 22' actuates member 23 and equalizer bar 25. The latter is connected at each end to rack bars 29 which mesh 25 with pinions 30 on the shaft of drum chart 31. The equalizer bar thus actuates the drum chart through rack bars 29 and pinions 30 and due to the springs 22 and 22' will be resiliently yet firmly driven by the draft 30 bar 19.

While there has been shown and described and pointed out the fundamental novel features of the invention as applied to a single modification it will be understood that various omissions and substitutions and changes 35 in the form and details of the device illustrated and in its operation may be made by those skilled in the art without departing from the spirit of the invention. It is the intention, therefore, to be limited only as indicated by the scope of the following claims.

40 I claim:

1. In a weighing scale, a cylindrical chart, an equalizer bar extending axially of said 45 chart for actuating the latter, a horizontally disposed load-actuated draft bar and a resilient connection between the draft bar and the equalizer bar.

2. In a weighing scale, a cylindrical chart, an equalizer bar extending axially of said 50 chart for actuating the latter, a horizontally disposed load-actuated draft bar disposed with a portion above the equalizer bar, and a resilient connection between said portion 55 of the draft bar and the equalizer bar.

3. In a weighing scale, a cylindrical chart, an equalizer bar extending axially of said 55 chart for actuating the latter, a load-actuated draft bar disposed parallel to the equalizer 60 bar, and a resilient connection between said draft bar and said equalizer bar at each end of the latter.

4. In a weighing scale, a cylindrical chart, an equalizer bar extending parallel to the 65 axis of said chart for actuating the latter,

a load-actuated draft bar, a member for carrying the equalizer bar, and springs bearing at one end upon said member and at the other end upon said bar.

5. In a weighing scale, a chart, an element 70 for actuating the chart, a load-actuated U-shaped draft bar, one of the sides of said bar being provided with an opening, a member having its shank disposed within said opening, said member being provided with an opening for receiving said element, and springs surrounding said shank and acting upon said member to cause it to move with said draft bar.

6. In a weighing scale, a chart, an element 80 for actuating the chart, means for supporting said element, a load-actuated member, a draft bar adjustably carried by said member, and a pair of springs between said bar and said supporting means, one of said 85 springs tending to move said means in one direction and the other spring to move said means in an opposite direction.

7. In a scale, a chart, a load-actuated member, counterbalances, a U-shaped element fastened to said member and connected to said counterbalances, a U-shaped member adjustably carried by said load-actuated member, a spring acting upon said U-shaped member, and an element for actuating the chart disposed within the bight of said U-shaped member and also acted upon by said spring.

8. In a scale, a drum chart, an equalizer bar disposed parallel to the axis of said chart 90 for actuating the latter, a load-actuated member having a bore therein, said member being connected to load counterbalancing means, a member adjustably mounted in said bore, and shock absorbing springs acting upon said latter member and also simultaneously acting 95 upon said equalizer bar.

9. In a weighing scale, a drum chart, a horizontal driving member therefor, a horizontally disposed load-actuated member disposed parallel to the driving member, and yielding means for connecting the said members.

In testimony whereof I hereto affix my signature.

WILLIAM GUMPRICH.
